UNITED STATES PATENT OFFICE.

WILLIAM J. WOODWARD, OF LEETONIA, OHIO.

HOT-WATER BOILER.

1,328,608.

Specification of Letters Patent. Patented Jan. 20, 1920.

Application filed January 10, 1919. Serial No. 270,533.

To all whom it may concern:

Be it known that I, WILLIAM J. WOODWARD, a citizen of the United States, residing at Leetonia, in the county of Columbiana and State of Ohio, have invented new and useful Improvements in Hot-Water Boilers, of which the following is a specification.

The invention relates to improvements in 10 hot water boilers, and seeks to provide, as its principal object, a device of this character which will have a longer life than devices ordinarily employed for supplying hot water.

15 A second object resides in a novel arrangement for producing the hot water to be used by means of heat transferred thereto from either boiler to which the heat is originally applied.

20 The invention is particularly serviceable when used in conjunction with gas heaters as it avoids the danger of stopping up the heating coil in the gas heater by contributing to the clean condition of the coil.

25 The invention consists essentially of a twin boiler one positioned within the other, the outer boiler receiving a quantity of water which is circulated through a gas heater, the heat of this water in the outer 30 boiler being transferred to the water in the inner boiler which is connected to the cold water supplied and which furnishes the hot water that is to be used. The water that is used in the outer boiler is always retained 35 therein and circulates only as a result of being brought into contact with the gas heater. Provision is made for the periodical replenishing of the water in this outer boiler by a valve controlled tap from the supply of the 40 inner boiler.

The invention is set forth in a specific embodiment, to which, however, it is not to be restricted. An actual reduction to practice 45 may suggest certain desirable changes or alterations, and the right is claimed to make any which do not deviate from the scope of the subjoined claims.

The invention is clearly illustrated in the accompanying drawings, in which:

50 Figure 1 is a vertical sectional view through the improved boiler.

Fig. 2 is a top plan view.

Fig. 3 is a transverse sectional view.

Referring to the drawing, there is shown 55 a boiler 1 in which there is centrally positioned a second boiler 2 whose bottom rests

upon the bottom of the boiler. This second boiler 2 is maintained in its central position within the outer boiler by appropriate stays 3, affixed between the sides of the two boilers. 60 The boiler 2 is provided with an appropriate drain 4 which of necessity must be carried through the wall of the outer boiler 1, at which point the outer boiler is appropriately calked to make it water tight. 65

The cold water is admitted to the boiler 2 through the pipe 5 which connects with the cold water supply and which passes through the top of the inner boiler 2 and terminates near the bottom of the latter, the point where 70 this pipe passes through the pipe of the boiler 2 being appropriately calked. A pipe 6 connects with the top of the boiler 2 and opens into the interior of the latter, this pipe connecting with various devices with which 75 it is desired to supply hot water.

The outer boiler 1 is designed to carry a quantity of water which completely envelops the boiler 2, and this water is intended to be heated by a gas heater 7 provided with a conventional coil 8 and gas burner 9 and with a suitable source of gas supply conducting the gas to the burner. The upper end of the coil 8 connects with the pipe 11 which communicates with the interior of the boiler 1 at a point above the top 80 of the boiler 2. The lower end of the coil 8 connects with the pipe 12 which communicates with the interior boiler 1 near its bottom. A drain cock 13 is connected in the 85 pipe 12 to permit the boiler 1 to be drained when desired.

A tap 14 is taken off the pipe 6 and connects with the pipe 11, this tap having a valve 15 connected therein, so that communication between the boilers 2 and 1 may be 90 opened and closed.

The top of the boiler 1 is closed by an appropriate sectional cover comprising two semi-circular sections 16 and 17 in which 100 provision is made for the passing therethrough of the pipes 5 and 6. These sections may be easily removed, so as to permit easy inspection of the interior of the boiler 1.

In operation, the boiler 1 is first supplied 105 with a quantity of water sufficient to completely envelop the boiler 2, this water being derived from pressure lines through the pipe 6, the tap 14, the valve 15, and the pipe 11. After a sufficient quantity of water 110 has been admitted to the boiler 1 the valve 15 is closed, whereupon the lighting of the

burner 9 will heat the water which has found its way into the coil 8. This heated water will rise in the pipe 11 and enter the boiler 1 and its place will be taken by cold 5 water which enters the coil from the bottom of the boiler 1 through the pipe 12. In this way, a circulation is set up in the boiler 1 and the water contained therein is raised to a uniform temperature. This hot water 10 surrounding the boiler 2 transfers its heat to the water contained therein and admitted thereto from the pressure main by the pipe 5. The boiler 2 is thus subjected to a uniform temperature and the water contained 15 therein is uniformly heated, the inner boiler deriving a longer lift because of its method of heating the water.

The arrangement of having an outer boiler supplied with a certain amount of 20 water which is not reduced by usage or in any other way except by evaporation, enables this water to be kept clean, as after the sediment has once been allowed to drop to the bottom, the water is circulated 25 through the coil 8 free from foreign substances which would tend to stop or clog the coil, thereby increasing the effectiveness 30 of the coil, since the absence of sediment

therein will permit the effective transfer of the heat of the boiler to the water which 35 passes through the coil.

What is claimed as new and useful is:

1. In a device of the kind set forth, a pair of boilers comprising an outer boiler and an inner boiler, means for connecting the 35 inner boiler to a pressure main, a water heater, connections between the water heater and the upper and lower ends of the outer boiler whereby a circulation may be set up in the latter, a valve controlled connection 40 between said means and said connections, and drains for both boilers.

2. In a device of the kind set forth, a pair of boilers comprising an outer boiler and an inner boiler, means for connecting the 45 inner boiler to a pressure main, a water heater, connections between the water heater and the upper and lower ends of the outer boiler whereby a circulation may be set up in the latter, a valve controlled connection 50 between the said means and said connections, the outer boiler being opened at its upper end, a sectional cover for said outer boiler, and drains for both boilers.

In testimony whereof I affix my signature. 55

WILLIAM J. WOODWARD.
